UNITED STATES PATENT OFFICE.

ARCHIBALD K. LEE, OF GALVESTON, TEXAS.

IMPROVEMENT IN APPARATUS FOR STEAMING AND CLEANING BARRELS, &c.

Specification forming part of Letters Patent No. **138,810**, dated May 13, 1873; application filed May 5, 1873.

To all whom it may concern:

Be it known that I, ARCHIBALD K. LEE, of the city and county of Galveston and State of Texas, have invented an Improved Method of Steaming Barrels for the reception of resin, turpentine, oils, molasses, sirups, and other like liquids, of which the following is a full, clear, and exact description, reference being had to the accompanying drawing and the letters of reference marked thereon making part of this specification, in which—

Figure 1 is a longitudinal section view. Fig. 2 is a top-plan view, the barrel-support being removed. Fig. 3 is a vertical sectional view.

The object of my invention is to provide an improved means of steaming barrels designed for the reception of resin, turpentine, oils, molasses, sirups, and other like liquids; and by which process of steaming I not only wash the barrel, but at the same time free it from impurities which might injuriously color or otherwise injure the liquids; and by the same process so tighten the joints as to render the barrels better suited for the purposes intended. The nature of my invention consists in constructing the vessel with a jacket or outer casing so arranged as to leave a steam-chamber, and which is provided with inlet and discharge tubes arranged, respectively, at the upper and lower sections thereof, and which chamber furnishes a means of heating the vessel to such a degree as to soften the gummy material which adheres to the barrel, and which permits of the same being more readily removed by the jets of steam emitted through the perforations of the rose, and which act directly on the interior surface of the barrel. My invention also consists in arranging along the lower section of the vessel, and running parallel with the steam-supply pipe, additional steam-pipes, and which not only serve to assist in heating to the desired degree the interior chamber of the vessel, but also provides, as it were, an open frame-support for the barrels to rest on during the process of steaming, and thereby facilitating the flow of all impurities from the barrel after the same have been washed off by the steam-jets. The nature of my invention also consists in the use of an open frame or barrel-support so formed as to

permit of its freely passing over the steam tubes and roses; and on which frame the barrels to be steamed are placed, and which affords a convenient means of introducing the barrels for the action of the steam, and of their removal after the same have been steamed and cleaned. I use in connection with the vessel two or more of these frames, so as to permit of the vessel's continued operation.

The construction and operation of my invention are as follows:

A is the steaming-vessel, which is constructed out of any suitable material and of any desired form. As represented in the drawing, it is rectangular, with a concave bottom, *a*. This style of bottom, owing to its arch formation, secures additional strength, while the gummy liquid produced by the steaming of the barrels is more readily drawn off. This vessel A may be of such dimensions as to provide an interior chamber of any desired capacity. I contemplate making the vessel of such dimensions as will provide a chamber of an area sufficient to readily accommodate and steam simultaneously twenty or more barrels; but, of course, there is nothing arbitrary about the size of the vessel or of its inner chamber, as my improvements are alike applicable to the vessel no matter what its size or dimensions may be. The wall A' of this vessel is surrounded by an outer casing or jacket, B', so arranged as to leave a closed steam-chamber, B, and which surrounds the sides, ends, and bottom *a* of the vessel. This steam-chamber B is provided with inlet and discharge tubes C C', one at the upper section and the other at its base, and respectively arranged as shown in Fig. 1. Along the lower section of the interior chamber of the vessel A runs and is secured a steam-supply pipe, D, and in openings in which are secured the vertical tubes D' D', each of which is provided with a rose, *d*. These roses *d* are perforated throughout their entire surface, and consequently emit lateral jets of steam, as well as jets in all other directions; and which is important, as each section of the barrel is thus subjected to the most direct and effective action of the steam. In the drawing only three of these tubes D and roses *d* are shown; but, of course, their

number will depend on the capacity of the chamber. When this, for instance, is such as to accommodate twenty barrels there will be twenty tubes and roses, and this number is increased or diminished in accordance with the capacity of the chamber. E E are steam-heating tubes, and are arranged parallel to and are in the same plane with the pipe D, as clearly shown in Fig. 2. These pipes E E, besides assisting the chamber B in properly heating the vessel so as to soften the gum on the interior of the barrels, and which permits of its being more readily removed by the action of the jets of steam, are also important for another purpose, as they serve as supports for the barrel to rest on during the process of steaming, and thereby permit the free flow and discharge of all impurities from the barrel after the same are washed off by the jets of steam, and which fall to the concave bottom *a* of the vessel and are drawn off by the cocks *e e*, Fig. 1. The pipe D and pipes E E are supplied with steam from any suitable boiler, as is also the chamber B. These pipes D and E E are supplied through a common nozzle, F, and branch pipes *f f*, which lead to the pipes E E. The nozzle F and its tube communicate directly with the pipe D, and is provided with a cock or valve, *f'*, which permits of the steam being shut off at pleasure, and thus preventing its discharge through the perforations of the roses while the frames H are being lifted out and in, and which not only prevents the waste of steam but also avoids all danger of the operatives being scalded while handling the frames. These pipes all lead to a common discharge-tube, F', and by means of which the condensed sediment, &c., are all readily drawn off as occasion may require. In inserting and removing the barrels I use a frame, H, which consists of forked side arms G G, to the base of which are secured flanged bearing-plates *g g*, and which serve as supports for two or more horizontal rods or plates, G' G'. These are on the same plane and parallel to each other, and are so arranged as to leave an unobstructed space at the center, sufficiently large to permit of the tubes D and roses *d d* readily passing therethrough, as clearly shown in Fig. 3. In eyes at the upper section of the forked side arms G G are secured the bail-arms H' H', and which are united at their upper section by the eye of the hook *h*, and which arrangement is clearly shown in Fig. 1. This hook *h* affords a convenient means of handling the frame, either by lever, pulley and cord, or other equivalent means.

I propose to use in connection with each vessel two or more of these frames, so that while one is supporting the barrels in the vessel and which are being steamed, another set of barrels is being arranged on frame No. 2 to be placed over the roses so soon as frame No. 1 is removed, and which permits of the work being carried on without interruption. These frames are constructed of any suitable mate-

rial, and their dimensions depend entirely on the size of the vessel in connection with which they are desired to be used. When the vessel is of capacity and is so arranged as to steam twenty barrels simultaneously the base-rods G' G' of the frame must be of length sufficient to support and hold twenty barrels in a row; and so in regard to a greater or less number, the size of the frame depending entirely on the dimensions of the vessel.

From the foregoing full and detailed description the operation of my improvement will readily be understood. The cock or valve *f'* is to so sit as to prevent steam passing to the pipe D, and steam is then, from a boiler or other vessel conveniently arranged, supplied to the nozzles C and F, the first filling the chamber B and surrounding the wall A' of the vessel, and the nozzle F, through the branch pipes *f f*, filling the pipes E E. The steam from this chamber B and the pipes E E soon thoroughly heat the interior chamber of the vessel. The barrels having been previously placed on the frame No. 1, and so arranged as to leave their bungs or open sections, through which they are filled, turned down and in position readily to be passed over the tubes D' D' and roses *d d*, the frame is lifted into the vessel and lowered down into its interior chamber, the bars or rods G' G' resting on and being supported by the pipes D and E E, and the tubes and roses entering the barrels, as clearly shown in Fig. 1. The heat of the vessel now soon softens the gummy substances and all other impurities that may have adhered to the surface of the barrels. The cock or valve *f'* is now opened, when instantly the steam rushes into the pipe D, up through the tubes D' D', and out through the perforations of the roses *d d*, and being dashed in all directions, soon thoroughly cleanses the barrel, while at the same time the joints between the staves are by the moisture so caused to swell as to become tight; the barrels being held by the pipes free from the bottom of the vessel, the steam, &c., readily runs out of the barrels, and is drawn off by the cocks *e e*. So soon as the barrels are thoroughly cleansed the valve or cock *f'* is closed, and frame No. 1 with its barrels is removed. Frame No. 2, having previously had barrels arranged therein, is now inserted and lowered over the tubes D' D' and roses *d d*, when the operation just described is repeated. The steam is drawn off from the chamber B and pipes E E by means of the cocks C' and F', as occasion may render desirable.

What I claim as new, and desire to secure by Letters Patent of the United States, is—

1. The vessel A having a steam-chamber, B, pipe D, tubes D' D', and roses *d d*, the whole being combined and arranged to operate substantially as described.

2. A vessel having steam-pipes D and E E arranged to heat the same, and at the same time serve as a supporting-frame for the barrels, in combination with the tubes D' D' and

roses *d d*, the whole being constructed and arranged to operate substantially as described.

3. The vessel *A* having a steam-chamber, *B*, formed as shown, pipes *D* and *E* *E*, tubes *D' D'*, and roses *d d*, the whole being combined and arranged to operate substantially as described.

4. In combination with a barrel-steamer, the frame *H*, constructed and arranged so as

to operate in connection therewith, substantially as described.

In testimony whereof I have signed my name to this specification in the presence of two subscribing witnesses.

ARCHIBALD K. LEE.
